ABSTRACT

[21] Appl. No.: 516,058

An improved flash fusing apparatus for fusing toner images onto flexible support material. First and second elongated flash lamps are closely spaced and a flexible support web bearing loose toner images on both sides is advanced along a predetermined cylindrical path encircling each of the flash lamps along its longitudinal axis exposing each side of the web to flash radiation from the lamps.

DUPLEX FUSING APPARATUS AND METHOD

The invention relates generally to flash fusing and in particular to a method and apparatus for fusing toner images onto flexible support materials. More specifically, this invention relates to a xerographic flash fusing apparatus and methods for rapidly and efficiently producing uniform duplex image fixing on each side of support material.

In the xerographic process, a plate, generally comprising a conductive backing upon which is placed a photoconductive insulating surface, is uniformly charged and the photoconductive surface then exposed to a light image of an original to be reproduced. The photoconductive surface is caused to become conductive under the influence of the light image so as to selectively dissipate the electrostatic charge found thereon to produce what is developed by means of a variety of pigmented resin materials specifically made for this purpose which are known in the xerographic art as "toners." The toner material is electrostatically attracted to the latent image areas on the plate in proportion to the charge concentration found thereon. Areas of high charge concentration become areas of high toner density while correspondingly low charge image areas become proportionally less dense. The developed image is transferred to a final support material, typically paper, and fixed thereto to form a permanent record or copy of the original.

Many forms of image fixing techniques are known in the prior art, the most prevalent of which are vapor fixing, heat fixing, pressure fixing or a combination thereof as described in U.S. Pat. No. 3,539,161. Each of these techniques, by itself or in combination suffer from deficiencies which make their use impractical or difficult for specific xerographic applications. In general, it has been difficult to construct an entirely satisfactory heat fuser having a short warm-up time, high efficiency, and ease of control. A further problem associated with heat fusers has been their tendency to burn or scorch the support material. Pressure fixing methods, whether hot or cold have created problems with image offsetting, resolution degradation and producing consistently a good class of fix. On the other hand, vapor fixing, which typically employs a toxic solvent has proven commercially unfeasible because of the health hazard involved. Equipment to sufficiently isolate the fuser from the surrounding ambient air must by its very nature be complex and costly.

With the advent of new materials and new xerographic processing techniques, it is now feasible to construct automatic xerographic reproducing apparatus capable of producing copy at an extremely rapid rate. Radiant flash fusing is one practical method of image fixing that will lend itself readily to use in a high speed automatic process as described in U.S. Pat. No. 3,529,129. The main advantage of the flash fuser over the other known methods is that the energy, which is propagated in the form of electromagnetic waves, is instantaneously available and requires no intervening medium for its propagation. As can be seen, such apparatus does not require long warm-up periods nor does the energy have to be transferred through a relatively slow conductive or convective heat transfer mechanism.

Although an extremely rapid transfer of energy between the source and the receiving body is afforded by

the flash fusing process, a major problem with flash fusing as applied to the xerographic fixing art, has been designing apparatus which can fully and efficiently utilize a preponderance of the radiant energy emitted by the source during the relatively short flash period. The toner image typically constitutes a relatively small percentage of the total area of the copy receiving the radiant energy. Because of the properties of most copy materials, as for example, paper, most of the energy incident thereon is wasted by being transmitted through the copy or by being reflected away from the fusing area. Another disadvantage associated with the prior art flash fusing apparatus has heretofore been the non-uniformity of image fixing produced. This phenomena is primarily due to the fact that it is difficult to produce highly uniform irradiance on a large receiving surface as for example a sheet of paper, from a relatively small source such as a flash lamp. This problem is further heightened in the case of duplex images on both sides of the paper.

While considerable effort has been expended in providing schemes for enhancing the efficiency and uniformity of fix of electrographic flash fusing systems, most efforts have been directed toward the provision of specially contoured reflecting surfaces which are designed to at least partially surround the flash lamp and thereby conserve energy via multiple reflections as set forth in U.S. Pat. No. 3,529,129. In addition to being costly to fabricate, such reflecting surfaces tend to become contaminated by loose toner particles and thereby necessitate frequent cleaning operations.

It is therefore an object of this invention to improve flash fusing of xerographic toner images on support material.

Another object of the invention is to accomplish flash fusing of either simplex or duplex electrostatic images with a single flash for a predetermined area.

Another object of the invention is to enable highly efficient fusing of toner images onto flexible support material.

Still another object of the invention is to fuse loose toner images on both sides of a support material simultaneously.

For a better understanding of the invention as well as other objects and further features thereof, reference is had to the following description wherein the FIGURE is a side view of a web of support material bearing xerographic toner images on each side thereof for fusing according to the present invention.

Referring now to the Figure in accordance with the present invention, loose image toner particles 10 and 11 deposited onto a flexible support web 12 at developer stations 14 and 15 respectively, are fused simultaneously. Web 12 is transported about the axes of elongated sources of radiant energy in the form of flash lamps 16 and 18. The web is advanced along the curved path of a guide track 20 by a driven roller 22 which is rotated in a direction indicated by the arrow. It will be appreciated that images 10 and 11 are moved along a circular path in each fusing zone such that the toner images are untouched and continuously face toward the center of curvature of the path where flash fusing lamps 16 and 18 are situated. It will be further appreciated that each of the flash fusing lamp fusing zones has a configuration which is circular or cylindrical such that uniform irradiance is insured to all points on the cylindrical surface from the particular flash lamp positioned

along the central axis thereof. In this manner, it is not necessary to fuse the images onto a support material in piece meal fashion by energizing the lamp a number of times as different portions of the toner images are transported past the flash lamp.

Flash lamps 16 and 18 are energized at predetermined intervals by a suitable control circuit. After simultaneous fusing of the images onto the web, the web can be cut into sheets and stacked by any suitable device.

It has been found that a Xenon flash lamp operating at power levels between 800 and 1200 Joules produces very good toner fusion. Pulse durations between 0.25 and 1.5 milliseconds were found to provide acceptable fusing with pulses between 0.5 and 1.2 milliseconds giving better fusing results. It has also been found that longer pulses of energy are required as the power level increases.

The efficiency of the duplex fusing system of the above-described invention can reduce the power required to fuse ordinary simplex copies by as much as 50 percent. It is believed that this is because of the unique configuration of the path through which the copy web is advanced past the flash fusing lamps. It will be further appreciated that the improved flash fusing system will provide improved efficiency even where images are on a single side of the web material.

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention.

What is claimed is:

- 10 1. An improved flash fusing apparatus for fusing toner images onto flexible support material comprising a first elongated flash lamp,
- 15 a second elongated flash lamp positioned closely adjacent to said first lamp, and means for advancing flexible support material bearing loose toner images along a predetermined path substantially encircling each of said first and second flash lamps along their longitudinal axes thereof to fuse the toner images thereto.
- 20 2. Apparatus according to claim 1 wherein said flexible support material is in the form of a web.
- 25 3. Apparatus according to claim 2 wherein the loose toner images are on each side of the web.
4. Apparatus according to claim 2 wherein track means guide the web along its predetermined path.
